UNITED STATES PATENT OFFICE

GEORGE EDWARD BJORKMAN, OF DJURSHOLM, SWEDEN

SHIELD FOR HAIR CURLERS

Application filed December 7, 1929. Serial No. 412,323.

This invention relates to improvements in shields for hair waving apparatus, being particularly directed to a novel form of shield to be used in association with a curler, particularly of the interiorly heated type, whereby the head of the patient may be protected from the heat effects being imparted to a particular strand or series of strands of hair, which are wound about a curler.

Further, it is an object of this invention to provide for a shield, comprising of two sections hingedly supported with respect to one another, and so constructed, when assembled with a curler containing a strand of hair therein, whereby the vapors developed in the waving of the hair may be restrained from passage onto the scalp or strands of hair adjacent that being acted upon.

Still further, it is aimed to provide a novel form of shield comprising of a plurality of strips of treated material pivotally mounted with respect to one another, and adapted to be drawn parallel to one another to enclose therebetween a curler containing a strand of hair to be treated, said elements forming the shield having formed therein a plurality of hems, the lower of which contains a filling material forming a pad for protecting the head or adjacent strands of hair, the other hem of which is adapted to carry the arms of a clamp through which the two sections are fastened together.

Still further, it is aimed to provide a novel form of shield comprising strips of impregnated material mounted adjacent one another, through the medium of fastening the same to the arms of a clamp, said strips having free ends extending interiorly, whereby the curler containing hair positioned in the shield may be adapted to rest between the projection and the body of the strip associated with said projection, thereby preventing any vapors formed during the waving operation with respect to a strand of hair

from passing downwardly and getting upon the scalp of the patient.

These and other advantages, capabilities, and features of the invention will appear from the subjoined detail description of one specific embodiment therefor illustrated in the accompanying drawings.

Figure 1 is a side elevation in section of the shield in actual functioning position.

Figure 2 is a front view of the shield partly cut out to show the relation of some of the elements therein.

Figure 3 is a plan view in section taken along lines 3—3 of Figure 2.

Referring to the reference characters in the drawings, numerals 9 and 9' represent strips of material of which the shield is formed, said strips of material being folded over so as to provide long and short arms 10 and 10' and 13 and 13' respectively, there being provided adjacent hems 11 and 12 and 11' and 12' at the bottoms of each of the same.

In manufacturing these shields to provide the device shown in Figure 1, each of the elements to form a shield is subjected to the following operations:

A piece of padding 14, such as flannel, is folded over on itself to form long and short arms 15 and 16, the folded over strip of padding is then laid on a flat strip of material 9, which is then folded over so that the short side 13 thereof corresponds to the short side 16 of the padding, and the long side 10 of the strip corresponds to the long side 15 of the padding. The strip containing the padding is then stitched as at 17 and 18 so as to form the two hems 11 and 12. The stitch 17 passes through 10 and 13 of the strip and 15 and 16 of the padding, to form the lower hem 12. The stitch 18 passes only through the arms of the strip 9 to form the second hem 11, at the same time providing a sufficient aperture in hem 11 through which may be passed one arm 90

of a clamp to be later described, the portion of the strips and padding included in the hem 12 being adapted to serve the purpose of forming a protective element for the head and the strand of hair passing into the shield.

As is shown in Figure 1, there is sufficient space in hems 11 and 11', since the upper projection of the shorter arm 16 of the padding 14 projects only slightly above the stitching 17, to provide for the passage of the arms 20 and 20' of the clamp 19, which arms are pivoted as at 21 and have associated separable locking elements 22 and 23 at the other end thereof. A second clamp 24 of the same nature and structural formation as that previously described, but applied independently of the strips and the padding, is adapted to surround the free upper arms 10 and 10' of the strips 9 and 9' to form a closure for the heating unit, having wound thereon a strand of hair, in conjunction with the closure formed by the clamp arms passing through the hems 11 and 11'.

As shown in Figures 1 and 2, a curler 25 comprising a resistance element imbedded in a phenolic condensation product, and having a pivoted clamp 26 thereon is adapted to be positioned in the shield, between the clips 19 and 24, being particularly disposed so that it rests between long and short arms 10 and 13 of one strip, or 10' and 13' of the other strip, so that there will be no leakage of vapor through the lower portion of the clip onto the scalp or hair of the patient.

In this manner, there is provided a simple shield element having a double function—for providing protection of the scalp of the patient being treated, in conjunction with a sealing device for preventing passage of vapors from the curler onto the scalp.

It is obvious that various changes and modifications may be made to the details of construction without departing from the general spirit of the invention as set forth in the appended claims.

I claim:

1. A shield for hair curlers comprising a plurality of strips of impregnated material, said strips being folded over to form long and short sections, and padding sections formed similarly of long and short sections, disposed between the long and short sections of each of said impregnated strips, hems formed adjacent the point of folding of the strips and the padding, the upper hem of each strip being adapted to have passed therethrough an arm of a clip, the lower hem of each strip being adapted to form a protective pad for the head.

2. A shield for hair curlers comprising a plurality of strips of impregnated material, said strips being folded over to form

long and short sections, and padding sections formed similarly of long and short sections, disposed between the long and short sections of each of said impregnated strips, hems formed adjacent the point of folding of the strips and the padding, the upper hem of each strip being adapted to have passed therethrough an arm of a clip, the lower hem of each strip being adapted to form a protective pad for the head, and a projecting portion of the short end of each strip, between which projecting portion and the body of the strip there is adapted to be positioned a curler having wound thereon a strand of hair.

3. A shield for hair curlers comprising a plurality of strips of impregnated material, said strips being fastened together at opposite sides to form an enclosing portion, a heater unit carrying a strand of hair positioned in said enclosing portion, each of said strips having free edges extending inwardly within said enclosing portion, either one of said edges of such strips being adapted to substantially surround the heater unit, and maintain said unit adjacent the body of the strip of which said edge is a part.

4. A shield for hair curlers comprising a plurality of strips of impregnated material, a clip fastening means having pivoted arms fastened to one of the sides of each of said strips, whereby to maintain the same in movable association with one another, so as to permit the enclosure of a curler carrying a strand of hair, and a second clip for fastening the free sides of said strips, whereby to form an enclosure for said curler, and means comprising projections integral with and extending inwardly from each of said strips for surrounding the curler within the area between the strips.

5. A shield for hair curlers comprising a plurality of strips of impregnated material, said strips being folded over to provide a plurality of long and short sections, padding strips similarly formed of long and short sections enclosed between the long and short sections of each of said strips, hems formed adjacent the point of folding of said strips, a clip having arms each passing through one of the hems of each strip, said clip being so formed as to mount the strips pivotally of one another for surrounding a strand of hair, said strips being fastened at the opposite end by another clip, whereby to form an enclosing portion for a curler.

6. A shield for hair curlers comprising a plurality of strips of impregnated material, said strips being folded over to provide a plurality of long and short sections, padding strips similarly formed of long and short sections enclosed between the long and short sections of each of said strips, hems formed adjacent the point of folding of said strips, a clip having arms each passing

through one of the hems of each strip, said
clip being so formed as to mount the strips
pivotally of one another for surrounding a
strand of hair, said strips being fastened
at the opposite end by another clip, where-
by to form an enclosing portion for a curler,
and means comprising projections formed
interiorly of the walls of the strips whereby
to surround and support the curler within
said shield.
